CHARLES T. WESTLAKE AND CHARLES F. FREDE, OF ST. LOUIS, MISSOURI, ASSIGNEES
TO DOUBLE BODY BOLSTER COMPANY, OF ST. LOUIS, MISSOURI, A CORPORATION OF
NEW JERSEY.

CAR-UNDERFRAME.

1,030,360.

Specification of Letters Patent. Patented June 25, 1912.

Application filed November 6, 1911. Serial No. 658,815.

To all whom it may concern:

Be it known that we, CHARLES T. WESTLAKE and CHARLES F. FREDE, citizens of the United States, residing at St. Louis, Missouri, have invented a certain new and useful Improvement in Car-Underframes, of which the following is a full, clear, and exact description, such as will enable others skilled in the art to which it appertains to make and use the same, reference being had to the accompanying drawings, forming part of this specification, in which—

Figure 1 is plan view of an underframe of our improved construction. Fig. 2 is a longitudinal section taken approximately on the line 2—2 of Fig. 1. Fig. 3 is a transverse section taken approximately on the line 3—3 of Fig. 1.

This invention relates generally to car underframes and more particularly to a platform casting intended particularly for use on that type of passenger cars which are provided with observation ends, although the platform with slight modifications can be advantageously used on various types of passenger cars.

Briefly our invention consists in combining in a single casting a double body bolster, a platform frame and a buffing sill, although, if desired, the buffing sill can be cast or formed separate from the platform and frame and connected thereto by bolts, rivets or in any suitable manner.

The object of our invention is to provide a strong, durable one piece cast structure which can be readily combined with the modern types of car bodies and which when combined with a car body materially strengthens the ends thereof, and providing a strong substantial underframe for the superstructure of the observation ends of the car.

To the above purposes our invention consists in certain novel features of construction and arrangement of parts hereinafter more fully described and claimed.

Referring by numerals to the accompanying drawings: 1 designates the center beam or the member of the double body bolster, and formed integral with the ends thereof are transversely disposed bolster members 2 the ends of which are formed integral with longitudinally disposed side sills or rails 3. Formed integral with the rear end 55 of the center member 1 is an extension 4 to

which the center sill or girder of the car underframe is attached. Formed integral with the forward end of the center member 1 is a forwardly extending sill or center member 5, and formed integral therewith adjacent the outer one of the bolster members 2 are transversely disposed members 6 which form the end sill of the underframe. The outer ends of this end sill are formed integral with extensions 7 of the side sills 60 3. The end sill 6 is preferably Z-shaped in cross section with its bottom flange 6^a projecting toward the end of the car, to serve as a base and support for the end posts of the car body. (See dotted lines Fig. 1.) 70 Formed integral with the outer end of the sill 5 are transversely disposed members 8 which form a vestibule platform supporting sill, and the ends of this last mentioned sill are formed integral with the forward 75 ends of the extensions 7 of the side sills. Formed integral with the outer end of the sill 5 is an extension 9 which forms the main body portion of the base or frame for the exposed portion of the platform, and formed 80 integral with the outer end of this extension 9 is a transversely disposed beam 10 which is preferably L-shaped in cross section and to which is fixed in any suitable manner the buffing sill 11. In some instances it may 85 be found desirable to cast the buffing sill integral with the extension 9. Formed integral with the beam or member 10 and with the sill 8 and end sill 6 is a series of longitudinally disposed beams 11^a the tops of 90 all of which occupy the same horizontal plane and serve as floor beams to which the metal plates forming the floor of the car are riveted, and corresponding beams 11^b extend between and are formed integral with 95 the end sill 6 and vestibule platform supporting sill 8. Pockets 12 are formed at the points where the sill 5 joins the end sill 6 and these pockets receive the lower ends of I-beam end posts 13. 14 designates end 100 posts which are preferably Z-shaped in cross section and these posts are arranged between the posts 13 and side sills 3 with their lower ends resting upon the bottom flanges 6^a of the end sill. The lower ends of 105 all of the end posts are rigidly fixed to the end sill by means of rivets or in any suitable manner.

Where a car body is combined with an underframe of our improved construction 110

the inclosed portion of the car body extends only to the end sill 6 and all of that portion of the underframe from said end sill to the extreme limits of the buffing sill 11 is used as an observation platform.

5 Our improved construction is very strong and rigid, is comparatively light in weight, materially strengthens the end portions of the car body and effectually resists service 10 strains and stresses.

It will be readily understood that minor changes in the size, form and construction of the various parts of our improved car underframe can be made and substituted for those 15 herein shown and described without departing from the spirit of our invention, the scope of which is set forth in the appended claims.

We claim:

20 1. A car underframe comprising a double body bolster, a center sill extension integral therewith, an end sill integral with said extension, a vestibule platform supporting sill integral with said extension and a buffer beam fixed to the outer end of the center sill extension.

25 2. A car underframe comprising a double body bolster, a center sill extension integral therewith, an end sill integral with the 30 said extension, a horizontally disposed bottom flange on said end sill, a vestibule platform supporting sill integral with the center sill extension and a buffer beam fixed to the outer end of said extension.

35 3. A car underframe comprising a double body bolster, a center sill extension integral therewith, an end sill integral with said extension, a vestibule platform supporting sill integral with said extension, a buffer 40 beam fixed to the outer end of the center sill extension and floor beams integral with the end sill and vestibule platform supporting sill and extending between said end sill and the buffing sill.

45 4. A car underframe comprising a double body bolster, a center sill extension integral therewith, an end sill integral with said extension, a horizontally disposed bottom flange on said end sill, a vestibule platform 50 supporting sill integral with the center sill extension, a buffer beam fixed to the outer end of said extension and floor beams integral with the end sill and vestibule platform supporting sill and extending between said end sill and the buffing sill.

55 5. In a car underframe the combination with a double body bolster, of a center sill extension, an end sill, an end post supporting flange integral with said sill a vestibule 60 platform supporting sill and longitudinally disposed floor beams all of which are formed in a single piece.

65 6. In a car underframe the combination with a double body bolster, of a center sill extension, an end sill, an end post support-

ing flange integral with said end sill a vestibule platform supporting sill, side sills uniting the sides of the double body bolster with the ends of the end sill and vestibule platform supporting sill and a series 70 of floor beams all of which parts are formed integral.

7. In a car underframe a double body bolster, a center sill extension integral therewith, an end sill and a vestibule platform supporting sill integral with said extension, a series of floor beams integral with and overlying the end sill and vestibule platform supporting sill and a buffing sill fixed to the outer ends of the floor beams. 75

8. In a car underframe a double body bolster, a center sill extension integral therewith, an end sill and a vestibule platform supporting sill integral with said extension, a series of floor beams integral with and overlying the end sill and sub end sill a transverse member connecting the outer portions of said floor beams and a buffing sill fixed to said transverse member. 80

9. In a car underframe the combination with a double body bolster, of a center sill extension integral therewith, an end sill integral with said extension, a bottom flange projecting outwardly from said end sill a 90 series of floor beams integral with and projecting outwardly from the upper portion of said end sill, and a transversely disposed vestibule platform supporting sill integral with the outer end of the center sill extension and positioned beneath the floor beams. 100

10. In a car underframe the combination with a double body bolster, of a center sill extension integral therewith, an end sill integral with said extension, a bottom flange projecting outwardly from said end sill, a transversely disposed vestibule platform supporting sill integral with the center sill extension, a series of floor beams integral with and projecting outwardly from the upper portion of said end sill which floor beams overlie the vestibule platform supporting sill and a buffing sill rigidly fixed to the outer ends of the floor beams. 105

11. In a car underframe a double body bolster, a center sill extension integral therewith, an end sill integral with said extension, a bottom flange projecting outwardly from the end sill, a series of floor beams integral with and projecting outwardly from the upper portion of the end sill, a transversely disposed vestibule platform supporting sill integral with the center sill extension and positioned beneath the floor beams, a transverse beam integral with 115 and connecting the outer ends of the floor beams and a buffing sill fixed to said transverse beam.

12. In a car underframe a double body bolster, a center sill extension integral 120

therewith, an end sill integral with said extension, a bottom flange projecting outwardly from the end sill, a series of floor beams integral with and projecting outwardly from the upper portion of the end sill, a transverse beam integral with and connecting the outer ends of the floor beams, a buffering sill fixed to said transverse beam and a vestibule platform supporting sill integral with the center sill extension and the floor beams which vestibule platform supporting sill is integral with the center sill

extension and the floor beams and is positioned between the buffer beam and the end sill.

In testimony whereof we hereunto affix our signatures in the presence of two witnesses, this 28th day of October, 1911.

CHARLES T. WESTLAKE.
CHARLES F. FREDE.
